CLAIM

The ornamental design for a gun cleaning kit case, as shown and described.

DESCRIPTION

FIG. 1 is a perspective view of a gun cleaning kit case, illustrating our new design;

FIG. 2 is a rear elevation view thereof;

FIG. 3 is a top elevation view thereof;

FIG. 4 is a front elevation view thereof;

FIG. 5 is a bottom elevation view thereof;

FIG. 6 is a right side elevation view thereof; and,

FIG. 7 is a left side elevation view thereof.

The broken lines in the figures show features of the gun cleaning kit case that form no part of the claimed design.
